UNITED STATES PATENT OFFICE.

EMMETT A. STEVENSON, OF ELIZABETH, NEW JERSEY.

AUTOMOBILE HOOD LATCH.

Application filed March 22, 1927. Serial No. 177,366.

The present invention is concerned with the provision of an automobile hood latch primarily adapted to prevent unauthorized opening of a hood and tampering with the 5 engine of a parked car.

To accomplish this purpose I preferably provide concealed automatically-acting latch means under the hood, and mount latch releasing means on the instrument board of 10 a car. Thus, with the hood down, and the car itself closed and locked, it is impossible for an unauthorized person to gain access to the engine.

An object of the invention is to provide a 15 hood lock of the general character above noted which may be readily attached to any standard make of car, which will be of simple, practical construction, extremely unlikely to get out of order, rugged and durable 20 in use, and well suited to the requirements of economical manufacture and convenient installation.

With the above noted and other objects in view, the invention consists in certain novel 25 features of construction and combinations and arrangements of parts, as will be more fully hereinafter set forth and pointed out in the claims. The invention may be more fully understood from the following description 30 in connection with the accompanying drawings, wherein—

Fig. 1 is a fragmentary longitudinal sectional view through the front of an automobile body showing rather diagrammatically my improved hood latch and its operating means.

Fig. 2 is an enlarged fragmentary view in 35 inside elevation showing the manner of mounting the latch and indicating in dotted lines the position of the latch and its associated parts when retracted.

Fig. 3 is a transverse sectional detail on the line 3—3 of Fig. 1.

In the drawings I have used the reference 40 character 10 to designate generally an automobile body including the usual longitudinally extending channelled chassis frame bars 11. The radiator has been indicated at 12, hood at 13, dash-board at 14, cowl at 45 15, and instrument board at 16.

The present invention is primarily concerned with the provision of a concealed hood latching means controlled from the instrument board.

The latching means at opposite sides of the hood are similar, and a description of one will suffice for both. A strip of metal 55 17 is formed with a right angular twist at its intermediate portion providing a flat upper end 18 to be riveted or otherwise secured 60 at 19 to the inner face of the hood near the lower edge of the latter, and to provide a depending bolt portion 20 extending below the edge of the hood and working through a slot 21 in the upper flange 22 of the chassis 65 frame bar 11.

A latch-bearing plate 23 is riveted or otherwise secured at 24 to the under face of the flange 22, and a latch member 25 is pivoted as at 26 between ears 27 depending 70 from the plate 23. This latch member is acted on by the end of a flat spring 28 secured to the plate 23, and normally rocked into the full line position of Fig. 2, wherein it will be noted that it enters a slot 29 in the 75 bolt 20. The upper surface of the latch provides a cam face at 30, so that in the ordinary operation of closing the hood, the lower end of the bolt will depress the latch to the dotted line position of Fig. 2 against 80 the action of its spring 28, and the latch will snap back into the opening 29.

Means is provided for withdrawing the latch 25 to release the bolt 20 and permit the sides of the hood to be freely hingedly lifted 85 in the usual manner. This means includes a flexible device 31 attached to a yoke 32 pivoted to the latch. The flexible device is preferably run through an armored cable 33 and connected to an operating handle 34 on 90 the instrument board.

It will be observed with particular reference to Fig. 2, that the latch member 25 is provided with a flat surface 25^a normally lying against the face of the latch plate 23 95 and limiting the rocking or swinging movement of the latch under the influence of its spring 28.

In operation the hood is closed in the usual manner, but in order to raise the hood again, it is necessary to have access to the operating handle 34 for withdrawing the automatic latches 25. It will thus be apparent that if the device is used on a closed car, the operator may park the car and lock 100 it with absolute assurance that the engine 105 will not be tampered with in his absence.

Various changes and alterations might be

made in the general form and arrangement of parts described without departing from the invention. Hence I do not wish to limit myself to the details set forth, but shall 5 consider myself at liberty to make such changes and alterations as fairly fall within the spirit and scope of the appended claims.

I claim:

1. The combination with an automobile 10 including channelled chassis bars and a hood, of a latch member in the chassis bar channel and a bolt on the hood working through a slot in the chassis bar and engaged by said latch, a plate secured to the under 15 face of the upper chassis bar flange, ears on the plate between which the latch is

pivoted and a spring on the plate urging the latch to bolt-engaging position.

2. The combination with an automobile 20 including channelled chassis bars and a hood, of a latch member in the chassis bar channel and a bolt on the hood working through a slot in the chassis bar and engaged by said latch, a plate secured to the under 25 face of the upper chassis bar flange, ears on the plate between which the latch is pivoted and a spring on the plate urging the latch to bolt-engaging position, said latch including a flat side engageable with the plate to limit movement of the latch in one direction under 30 the influence of the spring.

EMMETT A. STEVENSON.
